United States Patent Office

Des. 177,607
Patented May 8, 1956

177,607

BOTTLE

Edward Barq, Jr., Biloxi, Miss., assignor to Barq's Incorporated, Biloxi, Miss., a corporation of Mississippi

Application September 20, 1954, Serial No. 32,351

Term of patent 14 years

(Cl. D58—8)

The figure is a side elevational view of a bottle, showing my new design.

I claim:

The ornamental design for a bottle, substantially as shown.
